APPARATUS TO OPEN OR SHUT THE DOORS
OF AUTOMOBILESJin Nishimura, Tokyo, Japan, assignor to Jidosha
Koki Kabushiki Kaisha, Tokyo, JapanApplication June 8, 1936, Serial No. 84,223
In Japan April 30, 1936

2 Claims. (Cl. 268—3)

This invention relates to actuating mechanisms for automobile or other doors, in which a vacuum operating pump having a switch valve to open or shut the door is arranged at a suitable position in the automobile body, the said pump and a locking piece provided in the door being connected by suitable motion transmitting mechanism, and the portion of the said mechanism corresponding to the hinged part of the door being constructed as a flexible member, and has for its object to effect the opening and closing of the doors in an easy manner and from a point at a distance from the doors, such as the chauffeur's seat.

15 The drawings show one example of the apparatus to open or close the doors according to this invention; in which

Fig. 1A is a side view thereof, Fig. 1B a sectional view along line I—I in Fig. 1.

20 Fig. 2 is a plan view thereof.

Fig. 3 is a side view of the vacuum operating pump partly in section.

Fig. 4 is a plan view thereof.

25 Fig. 5 is a section of a buffer arranged in the said pump.

Fig. 6 is an end view of one form of switch valve adapted to be used for this invention, Fig. 7 is a longitudinal section thereof. Figs. 8, 9, and 10 are cross sections of the switch valve on line 7—7 in Fig. 7, and show the relative positions in which each part is set in three different working conditions.

In the drawings, 1 represents a rear portion of the side wall of the passenger compartment of 35 the automobile, 2 a door provided at the passenger's entrance, 2' a window of the door, 3 a front portion of the said side wall. A hinge 4 is provided to pivotally connect the said door to the rear portion of the side wall and includes a 40 pivot 5. A vacuum operating pump 6 is arranged horizontally in the space provided between the inner and outer plates constituting the rear portion of the side wall, while a switch valve 7 is fitted on a suitable part in the chauffeur's 45 compartment, for example, on the dashboard a control handle 7' is provided for the said valve. The valve 7 is connected through conduits 8 and 9 to both sides of the pump respectively, and through a conduit 10 to a vacuum producing portion of a carburetter for the automobile engine. Upon operating the valve 7 a vacuum is produced in the left or the right hand side of the pump 6, whereby the piston 11 is caused to move towards the left or the right hand direction. Clearance spaces 12 are provided between

the switch valve body and the corners of the valve box. The said clearance spaces allow the conduits 8 and 9 to communicate with the atmosphere through perforations 49, 50 and 51 hereinafter illustrated with respect to Figs. 7 to 10. 5

In opening the door 2, a locking piece 13 is released at the initial portion of the stroke of the pump 6, while the door is opened during the remaining portion of the said stroke.

In reducing this feature of the invention to 10 practice the piston rod 14 of the pump 6 is connected with a swivel rod 15 at its front end by means of a pivot 15'. A slide link 16 is arranged to move horizontally in the door. A connecting piece 17 is secured on the side of the 15 door to be hinged. The said connecting piece has a cylindrical member 18 extending into the door wall and receives the rear end portion of the slide link 16. The front end portion of a cylindrical member 19 is pivotally jointed with a rear cylindrical member 18' extending rearwardly from the connecting piece by means of a pin 20, and the front portion of the swivel rod 15 is slidably inserted in the rear portion of the cylindrical member 19. A flexible member 21 20 such as a spring is arranged between the front end of the swivel rod 15 and the rear end of the slide link in the space enclosed by the cylindrical member 19, the connecting piece 17 and the cylindrical members 18, 18'. Slits 22 (Figs. 3 25 and 4) are provided along the axis of the cylindrical member 19 and are adapted to receive projections 23 secured at the front end of the swivel rod 15.

Two guide rods 24 are secured at the front 30 end of the cylinder of the pump 6 and arranged parallel to the piston rod 14. A disc-like member 25 having a channel section is secured at the free ends of the said guide rods 24. The said member 25 and the cylinder of the pump 6 35 are firmly held by the inner and outer plates of the rear portion 1 of the side wall 3 by supporting members 26, 27 and 27'.

A buffer 28 is fitted at the front end of the pump and its cylindrical casing 29 has an inner ring shaped flange 30 in the front part thereof. A conically wound spring 31 is fastened at its large end to the said flange and at its small end to the central portion of a fine cylindrical body 32 inserted deeply into the said spring 31. 40 The cylindrical body 32 has a bottom plate 33 at its rear end. The rear end of a fine spring 34 45 inserted into the cylindrical body is fastened at the bottom plate 33, while its front end is secured to a valve stem 35' of a valve 35. The 50 55

buffer 28 composed of the aforesaid members is to be provided according to requirement, thus, when it is required to provide such a buffer, the conduit 8 communicating with the switch valve 7 is connected at the front end of the cylindrical casing 29, and an edge 36 of the connected portion is utilized as a valve seat for the valve 35. The valve 35 has a fine groove 37 on its surface, so that the pump 6 and conduit 8 are always in communication with the said fine grooves, even when the valve is seated.

Upon suitable actuation of the switch valve hereinafter described and provided on the dash board of the vehicle the space provided at the right hand side of the piston is connected to the vacuum portion, and the piston moves towards the right hand direction with the result that at the beginning of the movement, the slide link 16 is moved towards the right hand direction through the swivel rod 15 and flexible member 21, and through a lever 38 connected with the said link and horizontal member 40 the locking piece 13 is returned to impinge on a stop 44 against the action of a spring 43, whereby the door is held partially open. In this instance, the projections 23 secured at the front end of the swivel rod 15 reach the front end of the slit 22. On continuing the right hand movement of the piston 11, the connecting piece 17 secured at the rear side of the door is pressed through the swivel rod 15 and the cylindrical member 19, so that the door is opened outwardly around the pivot 5, as shown in Fig. 2. In this case, as the flexible member 21 extends into the space provided between the rear edge of the door and the front edge of the rear portion of the side wall, there is no difficulty in opening the door though the said transmitting mechanism may be distorted. On the other hand, when the switch valve is actuated in the opposite direction, the left hand side of the piston and vacuum portion are connected, and the air in the opposite side leaks through the clearance 12, so that the piston moves towards the left hand direction to shut the door, and at last, by the inertia of the door shutting motion, the locking piece is locked into the key hole provided in the side wall.

When the aforesaid buffer is provided, it prevents the sudden creation of a vacuum in the interior of the pump so that the door will be silently controlled. It is not however necessary to provide the said buffer.

One example of the switch valve to be used in this invention is shown in Figs. 6 to 10. The switch valve includes a valve box 45, while a communicating body 46 is inserted firmly into one end portion of the said valve box and provided with three nipples 8', 9', and 10'. The nipple 8' is connected with the conduit 8 to establish communication between the switch valve 7 and pump 6, the nipple 9' with the conduit 8 having the same communication as the conduit 8, and the nipple 10' with the conduit 10 to connect the valve 7 to the vacuum producing part in the automobile. A plug 47 is inserted from the other end of the valve box 45. This plug has a transverse hole 48 and three longitudinal grooves 49, 50, and 51 arranged at the quadrant points of a circle respectively as shown in Figs. 8 and 9. The control handle 7' as before mentioned is secured at the outside end of the plug stem 52. When the plug 47 is set in the position shown in Fig. 8, the conduit 8 is kept in vacuum, and the conduit 8 communicates through the groove 50 to the atmosphere, whereby the piston 11 of the pump 6 may

move towards the right hand direction. On the contrary, when the cock 47 is set in the position shown in Fig. 9, the conduit 8 is kept in vacuum, and the conduit 8 communicates through the groove 50 to the atmosphere, so that the piston 11 of the pump 6 is moved towards the left hand direction. Whereas, when the plug 47 is set in the position as shown in Fig. 10, the conduits 8 and 9 are both cut off from the vacuum portion and communicate to the atmosphere, whereby there will be no pressure difference between both sides of the piston 11 of the pump 6. In this latter case in which the piston 11 is not affected by vacuum, it is possible to control the door 2 manually. For this purpose, a slide member 40 secured at the locking piece 13 has a projection 40' at its outside, a lever 53 having a vertical groove 54 is secured at the swivel shaft 52 extending through the inner plate 3' and outer plate 3'', and the projection 40' is engaged in the groove 54. Therefore, when the shaft 52 is turned by means of the inside handle 57 or outside handle 56, the slide member 40 slides towards the right or left hand direction, so that the locking piece 13 is moved in the right or left hand direction.

What I claim is:

1. Door and latch control mechanism for motor vehicles comprising a cylinder, a piston adapted to reciprocate within said cylinder, a rod connected to said piston and projecting through one end of said cylinder, a slide member pivotally connected at one end to said connecting rod, a sleeve surrounding said slide member and connected to a door of the vehicle, lugs on said connecting rod, said sleeve having longitudinal slits intermediate its ends adapted to receive the lugs on said connecting rod, a slide rod connected at one end to the door latch and having its free end arranged in alignment with and adjacent to the free end of the connecting rod, said slide rod being adapted to be actuated by said connecting rod in one direction, and means for subjecting said piston ultimately on opposite sides thereof to pressure and suction for actuating said connecting rod, whereby the initial movement of said rod will unlatch the door and continued movement of said rod in the same direction will swing the door to open position.

2. Door and latch control mechanism for motor vehicles comprising a cylinder, a piston adapted to reciprocate within said cylinder, a rod connected to said piston and projecting through one end of said cylinder, a slide member pivotally connected at one end to said connecting rod, a sleeve surrounding said slide member and connected to a door of the vehicle, lugs on said connecting rod, said sleeve having longitudinal slits intermediate its ends adapted to receive the lugs on said connecting rod, a slide rod connected at one end to the door latch and having its free end arranged in alignment with and adjacent to the free end of the connecting rod, said slide rod being adapted to be actuated by said connecting rod in one direction, valve controlled means communicating with said cylinder on opposite sides of said piston and valve controlled mechanism for placing said cylinder into communication with atmosphere and suction alternately and on opposite sides of said piston for actuating said rod, whereby movement of said rod in one direction will unlatch the door and swing the latter into open position, while movement of said rod in the opposite direction will close said door.
